(57) CLAIM

The ornamental design for a transparent container for displaying purses and handbags, as shown and described.

DESCRIPTION

FIG. 1 is a front perspective view of the transparent container for displaying purses and handbags of the present invention;

FIG. 2 is front isometric view thereof;

FIG. 3 is a front view thereof;

FIG. 4 is a rear view thereof;

FIG. 5 is a right side view thereof;

FIG. 6 is a left-side view thereof;

FIG. 7 is a top plan view thereof;

FIG. 8 is a bottom plan view thereof; and,

FIG. 9 is an exploded view thereof.

Subject matter shown in broken lines forms no part of the claimed design.
